UNITED STATES PATENT OFFICE.

GEORGE W. WRIGHT, OF LAPEL, INDIANA.

LIQUID-FUEL-SUPPLYING APPARATUS.

1,275,349.

Specification of Letters Patent. Patented Aug. 13, 1918.

Application filed December 8, 1916. Serial No. 135,796.

To all whom it may concern:

Be it known that I, GEORGE W. WRIGHT, a citizen of the United States, residing at Lapel, in the county of Madison and State of Indiana, have invented a new and useful Liquid-Fuel-Supplying Apparatus, of which the following is a specification, reference being had to the accompanying drawings, and to the letters and figures of reference marked 10 thereon:

This invention relates generally to governing means in connection with a pipe line for regulating the movement of liquid from a source of supply to the terminal of the 15 pipe line, the invention having reference more particularly to the supplying of engines of the explosion type used on automobiles with liquid fuel from a supply tank and controlling the movement of the fuel 20 when pumped from the tank.

An object of the invention is to provide means whereby, when liquid fuel for supplying an automobile explosion engine is drawn from the supply tank by means of 25 the engine, the supply shall be reliably and accurately regulated to the needs of the engine whether the automobile is moving on a level road or up-hill or down-hill. Another object is to provide means for controlling the supply of liquid fuel so as to 30 permit gravity feed and to conveniently and economically make use of the engine suction for drawing the fuel from a supply tank, more particularly when the tank is at a 35 lower level than that of the carburetor of the engine to which the fuel is to be delivered.

A further object is to provide an improved fuel-supply controller of simple and reliable construction, which may be inexpensively 40 manufactured and be durable and economical in use and which may be so constructed as to permit the operations thereof to be readily seen, in order to ascertain whether or not the supply of fuel is being maintained.

With the above-mentioned and other objects in view, the invention consists in improved apparatus for controlling the action 50 of a pump and also the delivery of liquid drawn by the pump from a supply tank; the invention consisting further in the parts and in the combinations and arrangements of parts as hereinafter particularly described and further defined in the accompanying 55 claims.

Referring to the drawings.—Figure 1 is a side elevation of an automobile engine and the improved fuel-supplying apparatus arranged with respect to an automobile structure which is indicated by broken lines; Fig. 60 2 is a top plan of the liquid fuel-supplying apparatus and Fig. 3 is a side elevation thereof; Fig. 4 is a perspective view of the improved valve suitably comprising a part of the apparatus; Fig. 5 is a section on the line V—V on Fig. 3; Fig. 6 is a perspective view of one of the parts of the apparatus; Fig. 7 is a top plan of another part of the apparatus; Fig. 8 is a section on the line 79 VIII—VIII on Fig. 2; Fig. 9 is a section of 75 the apparatus on plane of the line IX—IX on Fig. 8; Fig. 10 is a section partially broken away on the line X—X on Fig. 2; Fig. 11 is a bottom plan of a float valve suitably comprised in the apparatus; and, Fig. 12 is a 75 central section of the valve on the line XII—XII on Fig. 11.

Similar reference characters on the different figures of the drawings indicate corresponding elements or features of construction 80 herein referred to in detail.

In the drawings the numeral 1 indicates the automobile structure, 2 the explosion engine to be supplied with fuel, 3 the intake manifold through which the engine is supplied with fuel, 4 the carburetor with which the engine is provided for a well known purpose, and 5 a fuel supply tank carried by the automobile.

The invention as preferably constructed 90 comprises a supplemental fuel-supply receptacle which has a bottom 6, a hollow cylindrical body part or wall 7 arranged on the bottom and a top 8 arranged on the body part, packing rings or washers 9 and 9' 95 being arranged in the joints at the ends of the body part. The body part preferably is composed of glass in order that the actions of the apparatus may be seen and especially so that it may be readily seen in case the receptacle becomes empty. The bottom and top are firmly secured to the body part of the receptacle by means of bolts 10, 10'. The receptacle is provided with a suitable device whereby it may be supported on the automobile, the top 8 preferably having an upwardly-extending arm 11 thereon adapted to be secured to the instrument board or dash of the automobile. The bottom 6 has a nipple 12 inserted therein upon which a check 100 105 110

valve 13 is normally seated and arranged in a valve cage 14 fixed on the top or inner portion of the bottom 6, and a pipe 15 is connected to the nipple and also to the supply tank 5 for conducting the liquid fuel to the receptacle. The bottom 6 has a valve casing 16 on its under side which has a bottom 17 having a neck 18 on its under side, and a duct 19 extends through the bottom and the neck. A pipe 20 is connected to the neck and also to the carburetor through which to supply the liquid fuel for the use of the engine. The upper or inner portion of the bottom 6 has an annular guide 21 thereon and the bottom has apertures 22 therein arranged around the guide to permit the liquid fuel to flow from the receptacle to the valve casing below. The under side of the bottom 6 has an annular valve seat 23 thereon that extends around the series of apertures and within the valve casing 16. A suitable float valve 24 is provided which may be composed of cork or otherwise adapted to float in liquid, the valve having a flat top 25 adapted to have contact with the seat 23 to practically close the apertures 22. The valve is of such size to permit it to rise or fall slightly in the valve casing and it has a flat bottom 26 that may rest upon the bottom 17 of the casing; the under side of the valve having radial grooves 27 to permit liquid to flow to the duct 19 when the valve is resting on the bottom of the casing. In operation the pipe 20 and the duct 19 may be filled with the liquid fuel and also some fuel may remain in the valve casing so that the valve floats up to or nearly to the seat 23, and when vacuum is created in the receptacle the valve is drawn to the seat to prevent fuel from being drawn back into the receptacle. Also when vacuum is created in the receptacle some of the liquid fuel is drawn into it from the tank 5 through the pipe 15 and prevented from returning by the action of the check valve 13.

45 In order to create vacuum in the receptacle a valve casing 28 is secured in a suitable aperture in the top 8 of the receptacle and has a duct 29 that extends from the interior of the casing to the interior of the receptacle, a valve stem 30 being provided which has screw threads 31 that are suitably fitted in the wall of the casing so that the stem is adjustable longitudinally, the inner end of the stem having a needle point valve 32 thereon adapted to partially close the duct 29. The valve stem is provided with a lock nut 33 that is seated on the outside of the casing, so that the valve shall be secured in position when properly adjusted to graduate the force of the suction produced by the engine and prevent excessive vacuum in the receptacle, the engine usually producing more suction than is required to draw the liquid fuel into the receptacle. A pipe 34 is connected with the valve casing and the in-

take manifold 3 of the engine and affords the necessary connection whereby to maintain the vacuum in the receptacle.

The vacuum in the receptacle is periodically changed in degree or fully destroyed automatically to permit the flow of liquid from the receptacle to the carburetor, and for this purpose a suitable vent is provided which preferably comprises a cylindrical guide wall 35 fixed upon the top 8 of the receptacle for guiding a valve, the top 8 having a port or duct 36 therein centrally of the guide wall. A conical valve 37 is arranged in the guide wall and is normally seated by the force of gravity in the upper end of the port 36 to permit vacuum to be created in the receptacle, the valve having an upwardly-extending shank portion 38 provided with guide wings 39 that extend outwardly beyond the valve to the guide wall, and the valve has a central socket bore 40 extending from the front of the valve and into the shank portion to receive an operating rod. The valve is retained in the guide wall by suitable means such as a cotter or other pin 41 inserted in the guide wall above the valve. The receptacle is provided with a suitable float 42 whereby to control the vent valve as the float ascends or descends with the fluctuating quantity of liquid in the receptacle. The float has a guide stem 43 on its bottom that extends into the guide 21 and has also on its top a guide stem 44 which constitutes a controlling element, a crosshead 45 being secured to the stem 44 by means of a set screw 46 or otherwise, the crosshead having a central aperture 47 which receives the stem and permits the crosshead to be adjusted longitudinally of the stem. The crosshead has guide-ways or openings 48 and 49 near its ends through which guide bars 50 and 51 extend respectively, the guide bars being secured to the top 8 of the receptacle and extending downward toward the float. The upper portion of the stem 44 has a guide bore or socket 52 into which the rod 53 extends so as to permit vertical movement of either the stem or the rod relatively to the other, the upper portion of the rod 53 extending through the port 36 and into the bore 40 of the vent valve in which the rod may move vertically to a limited extent without moving the valve. The rod 53 has a controlling device which is preferably formed as a disk 54 fixed to the rod so as to be above the stem 44. The guide bar 51 has a longitudinal slot 55 therein and is provided with a pivot 56 which extends across the slot and supports a trip device comprising an arm 57 that extends upwardly from the pivot so as to swing in the slot, the arm having an upwardly-extending stop finger 58 thereon to engage the guide bar above the slot. The arm 57 has a lateral projection or arm 59

thereon that extends toward the rod 53 to permit the disk 54 to be stopped thereon. The projection has a bevel end 60 adapted to be engaged by the disk when the latter is being elevated to retract the trip device and permit the disk to pass. The projection or arm 59 tends to act by the force of gravity to maintain the projection in advanced position but preferably is provided with a weight 61 to insure prompt action. The trip device comprises also an arm 62 that extends downwardly from the pivot and has an inclined back face 63 to be engaged by the wall of the aperture 49 when the crosshead descends for retracting the trip device, the crosshead sliding along the arm 62 during its movement.

The valve casing 28 is arranged on one side of the guide wall 35 and in some cases 20 is convenient for connection with the manifold of the engine, but in some cases it may be more convenient to arrange the casing on the opposite side which can be readily done by removing a plug 64 arranged in the top 25 8 and transposing the plug and the valve casing, the plug being adapted to close the opening in the top 8 after removing the valve casing, the latter being adapted to be secured in the opening prepared for the 30 plug.

In practical use, when the explosion engine is running the pistons as is well known act to produce suction in the manifold 3, and therefore suction is produced in the pipe 34 but its action is limited and controlled by means of the valve 32 which remains set when once adjusted. As the vacuum is produced within the receptacle the liquid fuel is drawn into the receptacle and also the 35 valve 24 is drawn to its seat 23. When the fuel accumulates to the desired extent the float rises and pushes up the rod 53 until the disk 54 passes the projection 59, the upper portion of the rod 53 rises in the bore 40 45 until the bottom of the bore is reached, after which the valve 37 is lifted from its seat and permits atmospheric air to enter the port 36, the air partially filling or destroying the vacuum which permits the liquid to 50 flow out through the apertures 22 to the valve casing below and thence through the pipe 20 to the carburetor. When the float descends a short distance the disk 54 is stopped upon the projection 59 while the 55 float continues to descend as the liquid flows out of the receptacle, the stopping of the disk preventing the valve 37 from becoming seated, but further downward movement of the float brings the crosshead into action 60 on the inclined face 63 and moves the trip device so that the projection 59 is withdrawn from beneath the disk 54 and permits the rod 53 and the valve 37 to suddenly drop and insure prompt closing of the port 36, 65 after which the vacuum is again produced

and the action of the apparatus repeated as before.

Having thus described the invention, what is claimed as new is—

1. Liquid-fuel supplying apparatus including a receptacle comprising a bottom and a side wall and also a top, the receptacle having an inlet and an outlet, the top of the receptacle being provided with a gravity-closed vent valve, a float in the receptacle to rise and open the valve, and means in the receptacle automatically acting to hold the valve open on descent of the float and adapted to be controlled by the descending float to permit the valve to drop to closed position.

2. Liquid-fuel supplying apparatus including a receptacle comprising a bottom having an inlet and an outlet, a side wall on the bottom, and a top on the wall having a duct therein; a vent valve vertically guided to close or open the duct and having a socket in its under portion, a float vertically guided in the receptacle and provided with an upright stem having a socket in its upper portion, an operating-rod extending movably into the valve socket and into the stem socket to be elevated by the stem, and means for controlling descent of the operating-rod.

3. In liquid-fuel supplying apparatus, the combination of a receptacle having an outlet in its bottom and a vent valve on its top, the valve closing by force of gravity, a chamber under said bottom in communication with the outlet, a float valve in the 100 chamber adapted to float up to said bottom and to close the outlet therein, an operating-rod for lifting and supporting the vent valve, a float in the receptacle and having a stem telescopically connected with the operating-rod, and means controlled by the float adapted to engage and momentarily hold the operating-rod on descent of the float.

4. In liquid-fuel supplying apparatus, the combination of a receptacle bottom having outlet apertures therein, the under side of said bottom having a valve-casing thereon extending about the apertures and provided with an outlet duct, a transparent side wall 115 secured upon said bottom, a top secured upon said wall and having a vent duct therein, a vent valve guided to close or open the vent duct and provided with an operating-rod, a float guided by means of said bottom 120 and said top and provided with means enabling it to control the operating-rod, and a valve in the valve-casing adapted to float in liquid and having a top adapted to be seated on said bottom to close said outlet 125 apertures.

5. In a liquid-fuel supplying apparatus, the combination of a receptacle comprising a bottom and a cylindrical side wall and also a top, said top having a duct therein,

- said bottom having an inlet and an outlet, a vent valve guided to close or open the duct and provided with an operating-rod, two guide bars in the receptacle secured to said 5 top, a float below the guide bars having a stem on its top adapted to control the operating-rod, and a crosshead secured to the stem and slidably connected with the guide bars.
- 10 6. In liquid-fuel supplying apparatus, the combination with a receptacle top and side wall, of a bottom secured to the side wall and having an outlet aperture therein, the under side of said bottom having an annular 15 valve-seat thereon extending about the aperture and also a valve-casing extending about the valve-seat, the valve-casing having a bottom provided with an outlet duct, and a valve in the valve-casing adapted to float in 20 liquid and having a top adapted to be seated on the valve-seat to close the outlet aperture, the bottom of the valve being adapted to rest on the valve-casing bottom and having a channel therein for passage of the 25 liquid to said duct.
7. In liquid-fuel supplying apparatus, the combination of a receptacle comprising a bottom and a cylindrical side wall and also a top, said bottom having an inlet and an 30 outlet, and also an annular guide on the inner side of the bottom, said top having a port therein and a cylindrical valve-guide on the upper side of the top extending about the port; a vent valve movable in the valve- 35 guide to close or open the port and provided with an operating-rod, and a float in the receptacle and having a guide stem on its bottom extending into the said annular guide, the float having also a stem on its top adapt- 40 ed to engage and lift the operating-rod to unseat the vent valve on upward movement of the float.
8. In liquid-fuel supplying apparatus, the combination with a receptacle bottom and 45 side wall, of a top secured to the side wall and having a vent-opening therein, the upper side of said top having a cylindrical guide wall thereon extending about the vent-
- opening, a valve adapted to seat in the vent-opening and having wings slidably engaging the guide wall, the valve having a socket in its under side, a stop device connected to the guide wall and extending over and above the valve, an operating-rod extending movably in the socket to support the valve, and means in the receptacle adapted to control the operating-rod to lift and support the valve and subsequently drop the valve with the operating-rod and permit the latter to descend in said socket. 50
9. In a liquid-fuel supplying apparatus, the combination of a receptacle comprising a bottom and a cylindrical side wall and also a top, said bottom having an inlet and an outlet, said top having a duct therein, a vent valve vertically guided to close or open the duct and having a vertical bore therein, two vertical guide bars in the receptacle secured to said top, one of said bars having a slot therein, a float movable below said bars and having a stem on its top, the top portion of the stem having a bore therein, a cross-head secured to the stem and having guide- 55 openings therein through which said bars extend, an operating-rod extending into the bore of the vent valve and the bore of said stem and movable vertically therein, the operating-rod having a stop collar thereon, and a trip device pivotally mounted in the slot of said bar and having a projection extending toward the operating-rod and adapted to be engaged by the stop collar and retracted on upward movement of the float, the projection normally being projected to engage the under side of the collar to support 60 the vent valve on downward movement of the float, said trip device having an arm adapted to be engaged by the crosshead to retract the projection on further downward movement of the float. 65
